UNITED STATES PATENT OFFICE.

VERNIE DEAN, OF DETROIT, MICHIGAN.

HOSPITAL OR SLEEPING GARMENT.

1,340,381.

Specification of Letters Patent. Patented May 18, 1920.

Application filed January 7, 1920. Serial No. 349,946.

To all whom it may concern:

Be it known that I, VERNIE DEAN, citizen of the United States, residing at Detroit, county of Wayne, State of Michigan, have 5 invented a certain new and useful Improvement in Hospital or Sleeping Garments, and declare the following to be a full, clear, and exact description of the same, such as will enable others skilled in the art to which it 10 pertains to make and use the same, reference being had to the accompanying drawings, which form a part of this specification.

My invention relates to a hospital and outdoor sleeping garment, shown in the accompanying drawings and more particularly described in the following specification and claims:—

One of the objects and principal purposes of this invention is to provide a sleeping garment adapted for either indoor or outdoor use in which the construction is such that when laundered it may be readily ironed by passing it between the rolls of a mangle.

One of the features of the present invention is the construction of a garment having straight parallel sides when folded flat, thereby providing for a regular uniform feed between the rolls of a mangle in much the same manner as is possible with sheets, table cloths or other flat work.

It being well understood that the ordinary shirt or garment of a like character, shaped in the usual manner to conform to the figure and provided with attached sleeves cannot be ironed by a mangle with any degree of success:—it is therefore one of the objects of the present invention to provide a garment which may be readily laundered at a minimum of expense.

40 A further object of this invention is to provide a construction in which the face of the wearer may be protected from inclement weather when worn as an outdoor sleeping garment and also to provide means whereby 45 a pillow may be retained in position to support the head without danger of displacement.

A further object of the invention is to provide the garment with detachable sleeves 50 if desired which may be removed for laundering, the construction of the sleeves being such that they may be readily fed between the rolls of a mangle without danger of being twisted, creased or wrinkled during the 55 process of ironing.

Another feature of the invention is to

provide an attached flap or apron adapted to cover the lower divided portion of the garment in order that when the bed covers are removed for attendance upon the patient 60 the divided portion of the garment will not be evident;—the appearance being much the same as though a sheet covered the patient.

With the foregoing and other objects in view which will appear as the description 65 proceeds the invention resides in the combination and arrangement of parts and in the details of construction hereinafter described and claimed it being understood that changes may be made in the precise embodiment of the invention herein shown without departing from the spirit of the same.

In the drawings accompanying this specification:—

Figure 1 is a front elevation of the garment with a portion of the apron removed to show its divided, or leg portion, also indicating in dotted lines a detachable cape forming the sleeves of the garment, which may be worn or not as desired.

Fig. 2 is a rear elevation of the garment showing the manner of securing the upper divided portion of the garment together when worn.

Fig. 3 is a cross-sectional view on line 3—3 of Fig. 2, and indicates the "flat" character of the garment when folded to go through the mangle.

Fig. 4 is a vertical sectional view on line 4—4 of Fig. 1.

Fig. 5 is an elevation of the detachable "cape" or sleeves, showing in dotted lines the rows of stitches forming the arms of the sleeves.

Fig. 6 is an elevation of the garment with a detachable head covering provided with a pocket to receive a pillow.

Fig. 7 is a fragmentary cross sectional view through the detachable head covering, attached to the garment.

Fig. 8 is an "inside" elevation of the detachable head covering showing the pillow in the pocket provided therefor.

Referring now to the letters of reference placed upon the drawings:—

A, denotes the garment as a whole, which is "substantially rectangular in shape when flat," the lower portion having a central slit B, forming legs C;—the edges of which are sewed together as indicated at D by dotted lines.

E, denotes an opening at the top of the

garment for the neck of the wearer;—the portions F, F, overlapping the shoulders being at substantially right angles to the sides G, G, of the garment. H, indicates 5 a row of stitches forming short sleeves or arms H'.

I, denotes a plurality of "tie tapes" for securing the overlapping side walls at the back of the garment. J, indicates an apron, 10 sewed along its upper edge to the body of the garment and covering the lower divided portion of the same that it may appear that the patient is covered with a sheet even through the regular bed coverings have been 15 removed.

K, indicates a detachable cape or sleeves and consists of a substantially rectangular portion of cloth having a central opening for the neck of the wearer, the ends of the 20 cape being sewed as indicated in dotted lines in Fig. 5 to form sleeves,—the lower edges being also sewed together if desired.

L, is a detachable head covering secured by a plurality of "snap" fasteners M to the 25 front of the garment, and is designed to protect the face of the wearer from inclement weather and may if desired be constructed of suitable water proof material.

The covering L folds back over the head 30 of the wearer, and is provided with a pocket L' to receive a pillow or cushion N, which is thus secured against accidental dislodgment.

Having thus indicated the several features 35 by reference letters it will now be seen that the garment when folded approximates in shape a table cloth, sheet, or other "flat work" and as the sides of the garment are parallel and at right angles to the ends of 40 the garment it may be easily "fed" through the rolls of a mangle without danger of wrinkling being thus ironed at a minimum expenditure of time and labor.

Having thus described my invention what 45 I claim is:—

1. A garment of the character described of bag-like shape having straight parallel side edges when flat, the ends being at right angles to the sides, rows of stitches extending 50 inwardly from the edges of the garment in spaced relation to its top to form sleeve openings at the sides thereof, the lower portion of the garment having a central slit, the

edges of the respective slitted portions being sewed together to form legs, the upper portion of the garment divided at the back to admit the wearer, and means for securing the divided portion of the garment together when in use. 55

2. A garment of the character described 60 of bag-like shape, having straight parallel side edges, the ends of the garment forming a right-angle with its side edges when folded flat, a neck opening at one end, an overlapping divided back communicating with the 65 neck opening, means for securing the walls of the divided back together when worn, lines of stitching extending inwardly from the straight side edges of the garment in spaced relation to the top edge of the garment, forming sleeve openings, the lower portion of the garment having a central slit with the edges of the slitted portion secured 70 together to form legs, and an apron secured to the body of the garment, adapted to overlap and hide its lower slitted or leg portion. 75

3. A sleeping garment having straight parallel side edges with ends formed at right angles thereto, its lower portion having a central slit parallel with its side edges, the 80 edges of the slitted portion being sewed together to form legs, an apron secured to the front of the garment adapted to cover its divided leg portion, and a detachable cape-like sleeve folded to overlap the upper portion of the body of the garment, said sleeve portion having straight parallel side edges, with ends cut at right angles thereto, the side edges being sewed together for a portion of their length to form sleeves. 85 90

4. A sleeping garment having straight parallel side edges with ends at right angles thereto when flat, a detachable head-cover of rectangular form adapted to be removably secured to the body of the garment and to 95 overlap the face and to extend beneath the head of the wearer, a cushion, and a pocket formed in the wall of said head cover portion to receive said cushion.

In testimony whereof I sign this specification in the presence of two witnesses. 100

VERNIE DEAN.
